UNITED STATES PATENT OFFICE

2,379,930

FILTER

William H. Sayler, Salt Lake City, Utah, assignor
of one-half to H. E. Bassford, Salt Lake City,
Utah

Application April 23, 1942, Serial No. 440,143

4 Claims. (Cl. 183—71)

My invention relates to filters and the like and has for its object to provide a new and highly efficient filter primarily for use in filtering dust and pollen from air, prior to entering an air conditioner unit.

A further object is to provide a highly efficient economically manufactured filter unit for filtering air and other gases and which unit may be quickly and easily cleaned or in drastic circumstances the filter may be quickly dismantled and the cloth thrown away and renewed or if only dirty the cloth may be washed and reused. Also in some cases the filter and frame may be simply turned so that the deposit side is down and the filter vigorously shaken, cleaning off all foreign particles from the collecting surface.

A still further object is to provide a simple filter which may be quickly immersed and washed for cleaning purposes without dismantling the filter from the frame.

These and other objects I accomplish with the device illustrated in the accompanying drawing in which similar numerals and letters of reference indicate like parts throughout the several views and as described in the specification forming a part of this invention and pointed out in the appended claims.

In the drawing,

Figure 1 is a vertical transverse section through one of my filters.

Figure 2 is a face view thereof.

Figure 3 is a sectional view of a modified cylinder used in the filter.

Figure 4 is an end view of Figure 3.

Figure 5 is a still further modified form of cylinder.

Figure 6 is an end view of Figure 5.

Figure 7 is a view to illustrate how the springs of the first form and the fabric are placed in the framework.

In the drawing in which I have shown my invention Figures 1 and 2 illustrate the invention in its simplified embodiment. The invention consists of a filter cloth A, of suitable material to filter foreign matter such as dust, pollen, and the like from the air and this cloth is made of a flat sheet of fabric of sufficient width and breadth to encompass a multiplicity of coil springs S which are used to hold the fabric in its proper place in the rectangular framework B. The cloth is secured to one edge of the top of the filter frame B by a plate held in place by screws 5 and from this face of the frame the cloth is folded or placed abutting against the inside of the top of the frame extending from the face where it is

secured to the opposite open face of the frame shown in the drawing as the fold or layer 7. A row of spaced apart springs 6 are then placed adjacent this fold of cloth and are so held apart until the cloth can be folded back over the first springs. This is designated as the fold 8 in the drawing. Another row of springs 6 is then placed in the spaces between the first springs, and so that the cloth is folded forward and back in the frame once with the full row of springs. Another row of spaced apart springs 9 is then placed against the fold or layer 8 of the filter fabric and the fabric again folded back covering these springs 9, leaving a space between each pair of springs in a like manner to that of the row 6 and the fabric is then folded back again to the opposite face of the frame B at which time the balance of the full row of springs 9 is placed abutting the fold of fabric in the space left between the first springs 9 and the fabric is again folded back in a like manner covering these last springs making ready for a third row of springs. This setting of the springs and covering by folding the fabric is continued until the entire frame B is filled with fabric enfolded springs S. The springs S are slightly offset in relation to the next alternating row to cover the most or greatest possible area of cloth surface and tiers of alternating rows of springs are set one on the other alternating, vertically and horizontally with the cloth covering the ends 10 of alternating rows 6 and the ends 11 of the alternating rows 9, thereby providing alternating elongated filtering sockets or openings spaced from each other by alternating rows of spring ends in one direction of travel of air when passing through the filter. Each end of the filter frame is provided with a retaining screen or framework so that forced draft through the filter will not dislodge the filter from its framework. The sides or edges of the cloth are held adjacent the side walls 14 of the frame by the spring pressure to hold them in filtering position and keep them from slipping from the filter spring.

The springs act as filter frames for the cloth and may be slightly tapered or may be evenly wound on a common axis with a common diameter. Other suitable frames may be used instead of the springs if desired such as a tubular frame 16 having transverse perforations 17 therein as shown in Figures 3 and 4 of the drawing or as shown in Figures 5 and 6 the tubular frame 18, may be made of a wire screen forming a tubular body. It will also be possible to use a refractory tube in some cases.

Having thus described my invention I desire to secure by Letters Patent and claim:

1. A filter comprising a framework; rows of springs carried in said framework; and fabric wound over said springs to form a fabric socket around each spring open at one end only, the fabric being so folded starting from the top of the framework that it encompasses spaced springs when folded in one direction and oppositely encompasses the springs filling the spaces between the first spaced springs when folded in the opposite direction and so interfolded around and over the rows of springs that they form opposed spaced apart individual columnar sockets in the fabric into which the air passes prior to passing through the filter fabric. 15

2. A filter comprising a framework; a sheet of fabric secured to said framework; rows of springs carried in said framework each row being set individually, in folds of said fabric spaced apart by another spring set into the fabric from the opposite side of the framework forming alternate spaced tubular sockets from each side of the framework for filtering air passing therethrough. 5

3. A device as set out in claim 1 including screens carried over each open end of the framework to hold the fabric and springs in position. 10

4. A device as set out in claim 2 including perforate means to hold the springs and filter fabric in the framework. 15

WILLIAM H. SAYLER.
